DESIGN FOR A DESK SIGN

Joseph K. Chun Fat, Honolulu, Territory of Hawaii

Application November 18, 1943, Serial No. 111,717

Term of patent 14 years

(Cl. D1—12)

To all whom it may concern:

Be it known that I, Joseph K. Chun Fat, a citizen of the United States of America, residing at Honolulu, Oahu, Territory of Hawaii, have invented a new, original, and ornamental Design for a Desk Sign, of which the following is a specification, reference being had to the accompanying drawing, forming a part thereof wherein:

I claim:

The ornamental design for a desk sign, as shown.

JOSEPH K. CHUN FAT.
